UNITED STATES PATENT OFFICE.

DONALD A. QUARLES, OF ENGLEWOOD, NEW JERSEY, ASSIGNOR TO WESTERN ELECTRIC COMPANY, INCORPORATED, OF NEW YORK, N. Y., A CORPORATION OF NEW YORK.

SIGNALING CIRCUIT.

Application filed October 26, 1922. Serial No. 596,928.

To all whom it may concern:

Be it known that I, DONALD A. QUARLES, a citizen of the United States, residing at Englewood, in the county of Bergen, State of New Jersey, have invented certain new and useful Improvements in Signaling Circuits, of which the following is a full, clear, concise, and exact description.

This invention relates to signaling circuits.

An object of this invention is to provide an anti-side-tone transmitting and receiving set for a signaling line.

Another object of this invention is to provide a high efficiency operator's transmitting and receiving set for talking and monitoring over telephone lines.

Another object of this invention is to provide an operator's talking and monitoring set for a repeater station which may be associated with the repeater without danger of causing the repeater to sing.

This invention is hereinafter described, in detail in connection with a telephone repeater station in which two-way amplified transmission is obtained through the intermediary of a three-winding transformer arranged in the form of a Wheatstone bridge network to prevent a local circulation of power when ever signals are received from either of the associated line sections. The equivalent of a three-wire circuit is employed in associating the operator's set with the repeater circuit. The middle branch of the three-wire circuit includes the operator's receiver, while the one side wire and the middle wire includes a monitoring winding on the three-winding transformer of one line section and the other side wire and the middle wire includes a similar winding of the three-winding transformer associated with the other line section to which the repeater is coupled. The transmitter of the operator's set is connected so as to impress the currents from the transmitter serially upon the two outside branches.

The drawing represents this invention applied to a 22 type repeater circuit.

The signaling arrangement comprises two line sections 4 and 5 coupled in the well-known manner by a 22 type repeater circuit to give amplified transmission for the signals in both directions between the two line sections. Block 6 indicates a suitable repeater or amplifier which may be of the

vacuum tube three-electrode type for receiving signals from line 4 and impressing them in amplified form upon line 5. Block 7 indicates a repeater for amplifying signals to be transmitted in the opposite direction. The input terminals of repeater 6 are coupled to the mid points of windings 8 and 9 while the opposite terminals of repeater 6 are coupled to the winding 10 of an output transformer which has its secondary winding in series with line 5. Similarly the input terminals of repeater 7 are connected to the mid points of line windings 11 and 12 while its output terminals are connected to winding 13 which is inductively associated with winding 8 and 9. Lines 4 and 5 are properly balanced by artificial lines marked "N." This arrangement insures that none of the output energy of repeater 7 will be impressed upon the input terminals of repeater 6 and that none of the output energy of repeater 6 will be impressed upon the input terminals of repeater 7.

In order to provide a talking and monitoring circuit for the line sections interconnected by repeaters 6 and 7, this invention provides a monitoring winding 14 associated with the transformer of line 4 and a monitoring winding 15 associated with the transformer of line 5. These monitoring windings are associated with the operator's receiver 16 and transmitter 17 by the equivalent of a three-wire circuit, winding 14 being included in series with one side wire 18 and middle wire 19 and the other winding 15 being included in series with the middle wire 19 and the other side wire 20. The operator's receiver 16 is as shown connected in series with the middle wire 19. The operator's transmitter 17 is coupled to the three-wire circuit by a transformer 21 so arranged that the currents from the transmitter are impressed serially upon the outside branches 18 and 20 of the three-wire circuit. If equal impedances are included between points 22 and 23 and between points 23 and 24 and if monitoring winding 14 is properly balanced by monitoring winding 15, it follows that none of the energy from transmitter 17 will be impressed upon the receiver 16 since the point 23 for the transmitted currents will be at the same potential as the common terminal of windings 14 and 15.

With this arrangement, incoming signals

from line 4 after being amplified by amplifier 6 will be impressed by monitoring winding 15 upon receiver 16, while incoming currents from line 5 after amplification by amplifier 7 will be impressed by monitoring winding 14 upon the receiver, so that the above described arrangement provides for amplified receiving or monitoring in both directions. Talking currents from transmitter 17 will be impressed simultaneously upon both line sections 4 and 5 through the intermediary of the windings 14 and 15. This is done in such a way that no tendency to sing is produced, since the energy transmitted through winding 15 to the line, similar to the action of winding 10, produces no potential differences upon the input terminals of repeater 7 and winding 14, similar to winding 13, will impress no potential differences upon the input terminals of repeater 16.

Another advantage of the arrangement just above described is that the monitoring windings 14 and 15 are so related that amplified signals from either the repeater 6 or 7 will not be fed back through the intermediary of the monitoring windings. Due to the three-wire connection above described the amplified signals from repeater 6 will 25 induce potentials in windings 15 but these potentials will not be impressed on winding 14 due to their anti-side-tone relation. That is, potentials induced in windings 15 by the amplified signals from repeater 6 will cause, 30 current to flow through wire 20, the winding of transformer 21 from terminal 24 to terminal 23, through receiver 16 and back to windings 15. This current will tend to divide at terminal 23 and part flow through 35 the transformer winding to terminal 22, through wire 18 and windings 14 back to windings 15. However, due to the inductive relation of that portion of winding 21 between terminals 24 and 23 and that portion 40 between terminals 23 and 22, a potential is set up in the latter winding by the current flowing in the former winding which balances the electromotive force tending to cause the current to flow through the windings 14 and so current will flow only 45 through the receiver 16 and through the transmitter 17. In other words, the transformer 21 with the four impedances 14, 15, 16, and 17, which are connected to it, forms 50 a biconjugate network. Similarly amplified signals from repeater 7 which will impress potentials upon winding 14 will not feed energy back through winding 15 upon the input terminals of repeater 7.

55 Still another advantage is that no complex artificial network is required in obtaining the anti-side-tone features of the operator's set since one of the monitoring windings is balanced against the other. Furthermore none of the energy from the trans-

mitter is lost in a balancing network such as is used in anti-side-tone substation circuits, but all of the energy from the transmitter is impressed on the two line sections through windings 13 and 15. 70

The invention claimed is:

1. A monitoring circuit for a telephone repeater station employing balanced repeater coils, comprising monitoring windings inductively associated with the line windings of said repeater coils, an operator's substation set comprising a transmitter and a receiver, and connections from said substation set to each of a plurality of said monitoring windings for balancing the impedance of one of said monitoring windings against the impedance of another of said monitoring windings to render said substation set anti-side-tone when transmitting from said transmitter. 75 80 85

2. A signal system comprising two transmission lines, a two way repeater circuit, a network for balancing each of said lines, a transformer for associating one of said lines with one of said networks and said repeater circuit, a second transformer for associating the other of said lines with the second of said networks and said repeater circuits, an auxiliary winding mounted on each of said transformers, a substation set comprising a transmitter and a receiver and connections from said substation set to said auxiliary windings for impressing currents from said transmitter serially upon said windings while preventing side-tone in said receiver. 90 95 100

3. A monitoring circuit comprising two outside branches, a central conducting path, a monitoring transformer winding in one of said outside branches, a second transformer winding in said other outside branch, means for inductively associating said windings with a signaling line for monitoring purposes, an impedance having said outside branches connected to different points thereof and having said central path connected to an intermediate point, a receiving device and a transmitting device, one of said devices being connected in said central path and the other of said devices coupled to said impedance. 105 110 115

4. In combination, two signaling lines, means for receiving signals from said lines, said lines being connected to said receiving means in substantially conjugate relation for preventing the transfer of signals from one of said lines to the other of said lines through said receiving means, and transmitting means for impressing signaling currents on said lines, said transmitting and receiving means being conjugate. 120 125

5. In combination, two signaling lines, two way repeating means interconnecting said lines, means for receiving signals from said lines, said lines being connected to said receiving means in substantially conjugate 130

relation for preventing the transfer of signals from one of said lines to the other of said lines through said receiving means.

6. In combination, two signaling lines, two way repeating means interconnecting said lines, means connected to said lines for receiving signals therefrom, said connections being provided with means for preventing the transfer of signals from one of said lines to the other of said lines through said receiving means.

7. A monitoring circuit comprising two outside branches and a central conducting path, a monitoring transformer winding in one of said outside branches, a second transformer winding in said other outside branch, means for inductively associating said windings with a signaling line for monitoring purposes, a receiver connected to said central path, an impedance having said outside branches connected to different points thereof and having said central path connected to an intermediate point, and a transmitter coupled to said impedance.

8. In combination two line sections, a repeater for repeating signals between said line sections in one direction, a second repeater for repeating signals in the opposite direction, an output transformer for coupling the output of each repeater to one of the line sections, and comprising a winding in circuit with the repeater and a winding in

circuit with the line sections, a third winding for each of said transformers, an operator's substation set comprising a transmitter and a receiver, and connections between said third windings and said substation set for balancing the impedance of one of said third windings against the impedance of the other third winding for preventing side tone in said receiver.

9. In combination, two line sections, a repeater for repeating signals in one direction between said line section, a second repeater for repeating signals in the opposite direction, an output transformer for each of said repeaters comprising a winding in circuit with the repeater and a winding in circuit with the line section, a third winding on each of said transformers, a three wire circuit comprising two outside branches and a central conducting path, one of said third windings being included in one outside branch, the other of said third windings being included in the other outside branch, a telephone receiver in said central path, a transmitter, and means for impressing currents from said transmitter serially upon said outside branches.

In witness whereof, I hereunto subscribe my name this 25th day of October A. D., 1922.

DONALD A. QUARLES.
